UNITED STATES PATENT OFFICE.

FREDERICK W. DAVEY, OF BROOKLYN, NEW YORK.

ELECTRIC HAMMER.

1,377,562.

Specification of Letters Patent. Patented May 10, 1921.

Application filed September 19, 1919. Serial No. 324,755.

To all whom it may concern:

Be it known that I, FREDERICK W. DAVEY, a citizen of the United States, residing in Brooklyn, in the county of Kings and State 5 of New York, have invented certain new and useful Improvements in Electric Hammers, of which the following is a specification.

This invention relates to electric hammers of the type in which the hammer or plunger member is reciprocated by means of electric solenoids which are alternately energized for drawing the reciprocating member back and forth.

10 The objects of the invention are to provide an efficient arrangement for reciprocating the hammer member, and to provide means for moving the hammer member from neutral position during the starting of the 20 operation thereof.

Another object is to provide an arrangement whereby the reciprocating member will be prevented from becoming permanently magnetized.

25 Other objects of the invention will appear as the description proceeds; and while herein minute details of the invention are described, the invention is not limited to these, since many and various changes may be 30 made without departing from the scope of the invention as claimed.

In the accompanying drawing, showing by way of example, one of many possible embodiments of the invention,—

35 Figure 1 is a central longitudinal sectional view showing the operating and controlling mechanisms of the hammer;

Fig. 2 is a sectional view taken on the line A—B of Fig. 1;

40 Fig. 3 is fragmental perspective view of the reciprocating plunger member; and

Fig. 4 is a fragmental elevation, partly in section, showing a detail of the hammer starting switch.

45 While my improved reciprocating mechanism is shown in connection with an electric hammer, it is understood that it may be used in connection with many other devices in which a member has to be reciprocated.

50 In the present instance, the reciprocating mechanism is shown embodied in an electrical hammer provided with a cylindrical casing 5 in the forward end of which is secured a forward head 6 provided with an axial

55 guide bore 7. In the rear of said casing there is secured a rear head 8 provided with

a handle 9. In said guide bore 7 there is loosely received the reduced end 10 of a tool spindle 11, said reduced end projecting into the casing chamber formed by said cylindrical casing and head.

Intermediately of said chamber there is disposed a disk 12 of tough insulating material provided with an angular central opening 13 (Fig. 2), and a plurality of radial bores 14 connecting with said central opening and disposed at right angles to each other. Said disk is held in place between a plurality of lugs 16 by screws 17 passing from the outside through said lugs and into the disk.

A guide tube 19 of bronze or other desired non-magnetic material and of square internal cross-section passes through said angular opening and terminates near said head. 75 Forward and rear solenoids 20 and 21 are disposed on said tube against said disk and are wound and connected up so as to have their like poles adjacent, for instance as shown, the letters S placed near the inner 80 end of each solenoid, and the letters N placed near the outer ends of the solenoids indicating that these may be either north or south poles respectively. The object of this will be presently explained. End disks 85 22 placed near the ends of the guide tube hold the solenoids in place.

A rubber buffer 24 is disposed within said guide tube 19 against the rear head 9; and within said tube, between said buffer and the tool spindle 11, there is slidably disposed a reciprocating member or plunger 26 (Fig. 3) of soft iron or other suitable magnetic conducting material provided with transverse front and rear openings 27 and 28 arranged staggered to each other and disposed a distance apart about equal to the length of the stroke of the plunger. A bushing 29 of insulating material covers said plunger and holds it out of contact with the guide tube 19. Said bushing is provided with large openings 30 at the ends of said transverse openings. Disposed within said large openings are contact plates 31 held in place by means of front and rear rivets 32 and 33 100 105 passing through said transverse openings and said contacts and electrically connected contacts of each pair with each other.

In each of said radial openings 14 there is slidably disposed a carbon brush 34 (Fig. 110 2), adapted to pass through the openings 35 in the tube 19 and engage said contact plates

31. Each brush is provided with a contact stem 36 projecting at the outer ends of the radial bore. A screw plug 38 closes the outer end of each radial bore and is provided with a central perforation through which said stem passes. A helical spring 39 compressed between the plug and brush presses the brush against the conducting plate 31 or the insulating bushing 29.
- 10 In the outer part of said handle 9 there is deposited an operating switch receiving bore 43 provided with an insulating lining 44. On the inner face of each lining is mounted a pair of spring contacts 45 and 46. An outwardly opening cup 47 is disposed in the outer end of said switch receiving bore, and is held in place by means of a shoulder screw plug 48 in the outer end of said bore and having a large central opening through which passes a push-button 50 provided with a flange engaging the inner face of said shoulder plug to prevent the entire removal of the button. A switch blade 52 screwed to said button passes 25 through a slot in the central wall of said cup and is adapted when the button is pressed inwardly against the action of the spring 53 to engage between and electrically connect said spring contacts 45 and 46.
- 20 An insulating block 55 is mounted across the interior of said bore and has mounted thereon a conducting piece 56 connected by means of the main conductor 57 to a terminal 58 engaged by nuts 59 on the end of 30 the stem 36 of one of the brushes. A branch conductor 61 connects said main conductor with the stem 36 of one of the adjacent brushes.
- 35 The other brushes opposite to said adjacent brushes are connected respectively by means of conductors 62 and 63 to one end of the front and rear solenoids 20 and 21 in such manner that the rear contact plates may be electrically connected with the rear solenoids when the plunger goes forward as 40 shown in Fig. 1, and the forward contact plates may be electrically connected with the forward solenoid when the plunger moves to the rear. Conductors 65 connect the other ends of the solenoid wires with the spring contact 46; and a conducting member 67 connects the other contact member 45 with one terminal of a source of current 70, the other terminal of which source is connected by means of a conductor 71 with said conducting plate 56.
- 45

55 From the above it will be seen that when the plunger is in the forward position as indicated in Fig. 1, and the button 50 is pressed by the hand of the operator, the current passes from the source of current through the conductor 71, the conducting piece 56, the main conductor 57, brush 34, the rear connecting rivet 33, the opposite brush 34, 60 the conductor 63, the solenoid 21, the con-

ductor 65, the spring contact 46, the switch blade 52, the other contact 45, and the conductor 67 to the other terminal of the source of current. This causes the current to energize the rear solenoid 21 whereupon the 70 plunger 26 is drawn to its rearmost position, and the forward rivet 32 is brought into contact with the brush 34 so that the current passes through the branch conductor 61, and the conductor 62, and the forward solenoid 75 20, thus energizing the forward solenoid and carrying the plunger forward to strike the tool spindle 11 to operate the tool. This operation is then continued so long as the button 50 is pressed.

80 As was noted, the solenoids 20 and 21 are wound to have their like poles adjacent, and therefore their magnetic flux flowing in opposite directions. The plunger 26, therefore, is first magnetized in one direction, 85 and then in the other. This will prevent the plunger from becoming permanently magnetized in either direction; and in this way one avoids the disadvantage of having the plunger to adhere too strongly to the tool 90 spindle when in the position of Fig. 1.

95 It sometimes happens, particularly when the hammer is placed in horizontal position that the plunger disposes itself at a mid-position so that neither rivet 32 nor 33 is in registration with the brushes, thereby preventing the passage of any current through the solenoid coils.

100 In order surely to move the plunger to one of its limits of movement while still holding the hammer in horizontal position, I have provided the following starting means: A transverse switch receiving recess 75 (Fig. 4), formed in the forward part 105 of the handle 9, is provided with an insulating bushing 76 and has disposed therein a pair of spring contacts 77 and 78 mounted upon an insulating support 79. An independent starting coil, wound with the solenoid coil 21, but entirely electrically independent 110 therefrom, has one of its ends 81 electrically connected to said main conductor 57 and its other end 82 electrically connected to the lower switch member 78. The upper switch member 77 is connected by means of 115 conductor 83 with said conducting member 67. Therefore, when the contact blade 85 (Fig. 4), secured to the starting button 86 is pressed inwardly, by the operator's thumb, against the action of the spring 87, it will 120 electrically connect said contact members 77 and 78, thus causing the flow of current through the conductor 71, the conducting piece 56, the main conductor 57, the end 81, the starting coil, the other end 82 of the 125 starting coil, the switch members 77 and 78, and the conductors 83 and 67, thereby completing a circuit through the starting coil drawing the plunger to its rearmost position whereupon a circuit is established 130

through the forward rivet 32, whereupon, after the starting button is released, the plunger reciprocates as explained before.

I claim:

5. 1. In combination, a plunger reciprocatable within limits, solenoid means for reciprocating said plunger; and means for moving the plunger when in a neutral position between said limits for reciprocation by said 10 solenoid means.
2. In combination, a plunger reciprocatable within limits; solenoid means for reciprocating the plunger; and means independent of the solenoid means for moving the 15 plunger when in a neutral position between said limits for reciprocation by said solenoid means.
3. In combination, co-axial solenoids; a plunger reciprocatable by said solenoids in 20 the solenoids and within limits; means for alternately energizing the solenoids; and means for moving the plunger when in a neutral position between said limits for reciprocation by said solenoids.
25. 4. In combination, co-axial solenoids; a plunger reciprocatable by said solenoids in the solenoids and within limits; means for alternately energizing the solenoids; means independent of said solenoids for moving 30 the plunger when in a neutral position between said limits for reciprocation by said solenoids; and means for energizing said independent means.
35. 5. In combination, co-axial solenoids; a plunger reciprocatable by said solenoids in the solenoids and within limits; means for alternately energizing the solenoids; means independent of said solenoids for moving the plunger when in a neutral position be- 40 tween said limits for reciprocation by said solenoids; and means for energizing said independent means; said independent means comprising a coil supported by one of said solenoids and electrically independent there- 45 from.
50. 6. In combination, a pair of co-axial solenoids; a plunger reciprocatable by said solenoids in the solenoids and within limits; means for alternately energizing the solenoids; means independent of said solenoids for moving the plunger when in a neutral position between said limits for reciprocation by said solenoids; means for energizing said independent means; and means for operating said independent means; said independent means comprising a coil wound with one of said solenoids and electrically independent therefrom.
55. 7. In combination, forward and rear- 60 ward solenoids; a plunger reciprocatory by said solenoids; means controlled by the plunger for energizing the solenoids when the plunger moves to one limit or the other; and separately controlled means for ener- 65 gizing one solenoid when the plunger is be- 70 tween limits.
8. In combination, forward and rearward solenoids; a plunger reciprocatable in said solenoids; insulating means around said plunger; conducting means passing through 75 said plunger; brushes for contacting with said conducting means; a main conductor connected to adjacent brushes; conductors connecting the remaining brushes with one end of said front and rear solenoids respec- 80 tively, in such manner that the forward sole- 85 noid is electrically connected to said main conductor when the plunger is in rear position and the rearward solenoid is connected to the main conductor when the plunger is in forward position; additional conductors connected to the other ends of said sole- 90 noids; and a source of current having one terminal connected to the additional conductors and its other terminal connected to said 95 main conductor.
9. In combination, forward and rearward solenoids; a plunger reciprocatory in said solenoids; insulating means around said plunger and carried thereby; conducting 90 members passing transversely through said plunger; brushes yieldably held in position to contact said conducting members; a main conductor connected to adjacent brushes; conductors connecting the other brushes 95 with one end of said front and rear solenoids respectively, in such manner that the front sole- 100 noid is electrically connected to said main conductor when the plunger is in rear position and the rear sole- 105 noid is connected to the main conductor when the plunger is in forward position; additional conductors connected to the other ends of said sole- 110 noids; and a source of current having one terminal connected to the additional conductors and its other terminal connected to said 115 main conductor.
10. In combination, forward and rear- 120 ward solenoids; a plunger reciprocatory by said solenoids; forward and rear conduct- 125 ing members passing through said plunger and arranged in staggered relation to each other; brushes held in position to contact opposite ends of said conducting members; a main conductor connected to adjacent brushes; conductors connecting the other brushes with one end of the wires of said front and rear solenoids respectively, in such manner that the front solenoid is electrically connected to said main conductor when the plunger is in rear position and the rear solenoid is connected to the main conductor when the plunger is in forward position; additional conductors connected to the other ends of said solenoids; and a source of current having one terminal connected to the additional conductors and its other terminal connected to said main conductor.

11. In combination, forward and rear solenoids; a plunger reciprocatory by said solenoids; forward and rear conducting members passing transversely through said plunger and arranged in staggered relation to each other; brushes between said solenoids and yieldably held in position to contact said conducting members; a main conductor connected to adjacent brushes; conductors connecting the other brushes with one end of the wires of said front and rear solenoids respectively, in such manner that the front solenoid is electrically connected to said main conductor when the plunger is in rear position and the rear solenoid is connected to the main conductor when the plunger is in forward position; additional conductors connected to the other ends of said solenoids; and a source of current having one terminal connected to the additional conductors and its other terminal connected to said main conductor.
12. In combination, a guide tube; forward and rear solenoids disposed on said tube; a plunger slideable in said tube and held against rotation therein; forward and rear conducting rivets passing transversely through said plunger and arranged in staggered relation to each other; pairs of brushes arranged between said solenoid, one pair to each rivet, and yieldably held in position to contact the opposite ends of said rivets; a main conductor connected to one brush of each pair; conductors connecting the other brushes with one end of said front and rear solenoids respectively, in such manner that the front solenoid is electrically connected to said main conductor when the plunger is in rear position and the rear solenoid is connected to the main conductor when the plunger is in forward position; additional conductors connected to the other ends of said solenoids; and a source of current having one terminal connected to the additional conductors and its other terminal connected to said main conductor.
13. In combination, a disk of insulating material provided with a central opening and radial bores; a guide tube of angular internal cross-section passing through said opening; forward and rear solenoids disposed on said tube against said disk; a plunger of angular cross-section slideable in said tube; forward and rear conducting rivets passing transversely through said plunger and arranged in staggered relation to each other and adapted to come in register with said radial bores; an insulating bushing covering said plunger; brushes slideable in said radial bores and yieldably held in position to contact said rivets; a main conductor connected to adjacent brushes; conductors connecting the other brushes with one end of said front and rear solenoids respectively, in such manner that the front solenoid is electrically connected to said main conductor when the plunger is in rear position and the rear solenoid is connected to the main conductor when the plunger is in forward position; additional conductors connected to the other ends of said solenoids; and a source of current having one terminal connected to the additional conductors and its other terminal connected to said main conductor.
